UNITED STATES PATENT OFFICE.

LEWIS B. STILLWELL, OF NIAGARA FALLS, NEW YORK.

SYSTEM OF ELECTRICAL DISTRIBUTION.

SPECIFICATION forming part of Letters Patent No. 633,920, dated September 26, 1899.

Application filed May 24, 1899. Serial No. 718,090. (No model.)

To all whom it may concern:

Be it known that I, LEWIS B. STILLWELL, a citizen of the United States, residing at Niagara Falls, in the county of Niagara and State 5 of New York, have invented a new and useful Improvement in Systems of Electrical Distribution, of which the following is a specification.

My invention relates to systems of electrical 10 distribution, and particularly to means employed for protecting such systems from injuries resulting from short circuits and overloads.

The object of my invention is to provide an 15 effective means for localizing the interruption of service which in electric-power plants is likely to be caused by a short circuit or overload upon one of the branch circuits of the system.

20 In large systems of electrical generation and distribution it is usual to transmit the electrical energy from the generating-station to a plurality of substations, and from each substation energy is distributed for lighting 25 and power purposes in various directions by local feeder-circuits.

If circuit-breakers or fuses of ordinary types be used, a short circuit upon one of the feeder-circuits radiating from a substation 30 will frequently result in a total interruption of service from that substation and will sometimes result in a total interruption of the service from all substations which are supplied through the main transmission-circuit, 35 since it is liable to open not only the circuit-breakers or fuses in the feeder-circuit first affected, but also to open the circuit-breakers or fuses through which the entire amount of power delivered to the substation is conveyed 40 and in some cases even the circuit-breakers or fuses at the main station.

In the case of circuit-breakers of the ordinary type, even where dash-pots are used for delaying the opening movement, the time 45 which elapses after the short circuit is established before the circuit-breaker acts depends upon the quantity of current which flows in the circuit—*i. e.*, upon what is ordinarily termed the “severity” of the short circuit.

50 In cases where my present invention is em-

ployed the time which must thus elapse is absolutely independent of the severity of the short circuit. It is thus made possible to open with certainty any branch or feeder which may become short-circuited without any risk 55 of cutting off the supply of power from other branches or feeders of the system.

My invention is illustrated in the accompanying drawings, in which—

Figure 1 is a diagrammatic view of a circuit-breaker constructed in accordance with my invention and in closed position. Fig. 2 is a view corresponding to Fig. 1, but showing the circuit-breaker open. Fig. 3 is a diagram of a system of distribution embodying 65 my invention.

Referring now particularly to Figs. 1 and 2 of the drawings, 1 is an electric conductor forming one side of a circuit to be protected and including the primary winding 2 of a 70 transformer 3, one terminal of the secondary winding 4 of this transformer being connected to one terminal of a coil 5 of a magnet 6. The armature 7 for the magnet is pivotally mounted upon a suitable bracket or other 75 support 8 and has an arm 7^a extending beyond the point of support, so as to engage with a pin 9, projecting laterally from a substantially vertical rod 10. The rod 10 is pivotally connected at its upper end to a holding-pawl 80 11, the free end of which, when in the position shown in Fig. 1, engages with one of the teeth of an escapement-wheel 12 of a clock-train 13. The pawl is normally held in this position by means of gravity and the action of a coiled 85 spring 10^a, interposed between a portion of the bracket 6 and an adjusting-nut 10^b on the lower end of the rod 10. The clock-train 13 when free to move may be operated by a spring or weight and regulated in any well-known manner, so as to rotate at a certain 90 definite speed a wheel or disk 14, the body of which is preferably formed of insulating material and is provided with a conducting-strip 15, which extends over a portion of its periphery. A contact finger or brush 16 engages with the periphery of the wheel 14 and constitutes the terminal for one end of the transformer secondary 4 and also for one end of the coil 17 of a magnet 18. The other end of 100

the coil 17 and one end of the coil 5 are suitably connected together and to the rim 15 of the wheel 14 by any suitable means.

The circuit-breaker proper may be of any suitable form adapted for automatically opening an electric circuit. In the present case I have shown it as comprising a pair of stationary terminals 19, a bridging movable terminal 20, toggle-levers 21, a handle 22 for moving the member 20 into engagement with the terminals 19, and a latch 23, constituting an extension of the armature 24 of the magnet 18.

It will be understood from the construction here illustrated and described that so long as the parts are in the position shown in Fig. 1 and the current in the circuit does not rise above the amount for which the clock-train-releasing mechanism is adjusted there will be no movement of the clock-train or of the circuit-breaker. If, however, the current increases to such an amount as to cause the magnet 6 to exert a pull upon the armature 7 sufficient to overcome the action of gravity and that of the coiled spring 10^a, the pawl 11 will be raised out of engagement with the escapement-wheel 12 and the clock-train will operate to rotate the wheel 14. So long as the brush 16 is in contact with the rim 15, however, the coil 17 of the magnet 18 will be short-circuited and the circuit-breaker will not operate. When the wheel 14 has rotated a sufficient distance to bring the brush 16 onto the insulation portion of the wheel-periphery between the ends of the rim 15, the current in the secondary circuit will necessarily be compelled to traverse the coil 17 of the magnet 18, and the latter will attract its armature 24, and thus withdraw the latch 23 and permit the circuit-breaker to open, as is indicated in Fig. 2.

Referring now to Fig. 3 of the drawings, the main generating-station or source of power is represented by an alternating-current generator A, and the main transmission-conductors 1 and 1^a are protected from short-circuits and overloads by the circuit-breaker mechanism B, having an operative connection with the conductor 1 by means of the transformer 3, the same as is indicated in Figs. 1 and 2. C and D represent two substations, respectively provided with circuit-breaking apparatus C' and D' similar to that already described, and from each station subfeeders to any desired number may extend in various directions for supplying either light or power, or both, for local consumption. Two of such circuits c c' and c² c³ are shown as branching from the substation C. The subfeeder c is provided with a circuit-breaker C² and the subfeeder c³ with a circuit-breaker C³, which may be the same in construction and mode of operation as already described. The number of substations and the number of subfeeders branching from any one or all of them may be anything desired, and my invention is therefore not limited in this regard.

I desire it also to be understood that my invention is also intended for use in connection with polyphase circuits of any practical number of phases and that the protecting means described may be connected to each side of each circuit or to two conductors of a three-phase circuit.

In utilizing my invention in a system such as is generally indicated in Fig. 3 the time element of the circuit-breaker will open only at the end of a predetermined interval of time after the time-measuring mechanism begins to operate.

In order that the opening of each circuit may be rendered independent of all the others, I propose to so set the circuit making and breaking element of the time-measuring mechanism or device—this element, as shown, being the wheel 14—pertaining to each circuit-breaker that the time period which will elapse before the breaker will act will be of different length from that of any other controlling or dependent circuit. For example, each of circuit-breakers C² and C³ may be set to open at an interval of, say, two seconds after the occurrence of a local short circuit, circuit-breakers C' and D' after an interval of four seconds, and circuit-breaker B after an interval of six seconds. It will thus be seen that should the trouble occur at any point other than at the main station the particular circuit where the trouble occurs will be opened before the circuit-breakers at other points which are set for a greater time limit will have an opportunity to open.

It will be understood that my invention is not limited to any specific time-measuring device or to any particular type of circuit-breaker, and that where I have illustrated and described magnets and armatures solenoids and movable cores may be employed.

I claim as my invention—

1. In a system of electrical distribution consisting of a main supply-circuit and two or more subordinate or distributing circuits which receive energy from the main circuit, an automatic circuit-opening device controlling the main supply-circuit, and an automatic circuit-opening device controlling one or more of the subordinate distributing supply-circuits, these circuit-breakers being severally provided with time-measuring mechanisms so adjusted with reference to each other that in case of a short circuit upon a subordinate circuit, the circuit-breaker controlling the subordinate distributing-circuit must operate before the circuit-breaker controlling the main circuit operates.

2. In a system of electrical distribution, a main supply-circuit and a plurality of subordinate distributing-circuits, in combination with a circuit-breaker for each circuit and a time-measuring controlling device for each circuit-breaker, each of said devices corresponding to a subordinate circuit being set to insure the opening of its breaker before

the breaker of any dominating circuit can be automatically opened.

3. In a system of electrical distribution, a main supply-circuit and one or more subordinate distributing-circuits supplied thereby, in combination with a circuit-breaker in each of said circuits and time-measuring mechanism for each circuit-breaker provided with means for insuring the opening of the breaker

a predetermined interval of time after the beginning of an excessive flow of current in its circuit.

In testimony whereof I have hereunto subscribed my name this 16th day of May, 1899.

L. B. STILLWELL.
